UNITED STATES PATENT OFFICE.

JOSHUA G. BENSTER, OF DUNCAN, NEBRASKA.

WINDMILL.

SPECIFICATION forming part of Letters Patent No. 336,784, dated February 23, 1886.

Application filed March 22, 1884. Serial No. 125,158. (No model.)

To all whom it may concern:

Be it known that I, JOSHUA G. BENSTER, of Duncan, in the county of Platte and State of Nebraska, have invented a new and useful 5 Improvement in Windmills, of which the following is a full, clear, and exact description, reference being had to the annexed drawings, forming part of this specification.

This invention relates to solid vertical-wheel windmills; and the invention consists of the novel construction hereinafter described and claimed.

In the drawings, Figure 1 is a side elevation of my improved windmill, partly in section. 15 Fig. 2 is a plan view of the motion-converting device, and Figs. 3, 4, and 5 are detail views.

A indicates a tower, which may be formed of four timbers connected together at the upper ends by an annular plate, B, which forms a 20 bearing for a rotary mast, C, which is supported in a socket, D, at its lower end. The mast is made in two pieces, c c', which are pivoted together at c' at one side of their longitudinal center in such manner as to form a 25 knee-joint. The pieces c c' are pivoted together at one side of their longitudinal center to cause the upper piece, c', always to incline from a perpendicular, more or less, according to circumstances, as hereinafter explained.

The wheel-hub E is loosely mounted on an axle, F, consisting of a pin inserted through the upper end of the piece c' of the mast, and which may be secured by a nut. To prevent 30 the weight of the wheel from deflecting the piece c' downward, a cord, G, is attached to the lower end of said piece and carried over a sheave, H, supported in the piece c, and is strung through a series of weights, I, arranged 35 one above another, and is secured to the last one of the series. The weights are made cylindrical in form, and are provided with circular flanges i at their upper ends, by which they, except the lowest weight, may be sup-

40 ported in annular supports J, attached to the piece c, to suspend their action on the cord when the wind is not strong enough to deflect the piece c' downward. In the latter case the bottom weight I, which alone acts upon the 45 cord, will be sufficient to hold the piece c' erect; but when the force of the wind amounts

to a gale the resistance of the bottom weight will be overcome, and said weight will be drawn up until it comes in contact with the next weight above it, lifting this second weight 55 above its support J, and thus causing it to act on the cord, and so on throughout the series of weights, as the gale increases in force, until the piece c' is sufficiently deflected to act as a vane and cause the mast to rotate to bring 60 the plane of the wheel in alignment with the direction of the wind. When the force of the gale subsides, the weights, being all supported on the cord G, will cause the piece c' to resume its upright position, and the force of an 65 ordinary wind will then cause the wheel to face the wind in position for being rotated thereby.

The wheel-hub E is provided with a chain-pulley, K, and this pulley is connected by an 70 endless chain, L, with a chain-pulley, M, supported in the lower end of the mast. This chain is guided over the upper or front side of the knee-joint by a chain-pulley, N, supported in piece c', and over the under or rear 75 side of the knee-joint by a roller, O, attached to piece c', between which roller and piece c' the chain is arranged. The axle of the pulley M in the lower end of the mast is provided with a crank, P, having a roller, p, thereon, 80 which roller is arranged between two parallel annular guide-plates, p' p'', which inclose the lower end of the mast, and are attached to two arms, p'', which are trunnioned in two of the timbers of the tower.

With this construction, as the wind-wheel revolves and the chain L is set in motion, the crank P will be rotated, and its contact by roller p with the plates p' p'' will cause the arms p'' to oscillate on their trunnions, giving 85 a reciprocatory motion to the pump-rod Q, attached to the lower plate, p''. A rotary motion may be obtained from the axle of the chain-pulley M', yet to be described.

R indicates a circular table, having its periphery loosely supported in recesses r, formed in the four timbers of the tower, and having a central opening for the mast. On opposite sides of said opening are cleats r' and keys r'', by which the table may be secured to the mast, 90 so as to be able to rotate therewith. Just above the table is the said chain-pulley M', 95

with which the chain L engages, said pulley being supported on a shaft passing through the mast.

The object of the table and pulley M' is to utilize the mill for driving small machines—such as churning, grindstones, or other devices requiring a rotary motion—the rotary table serving to carry the machine around with the mast under varying conditions of the wind, so as not to allow the relations of the machine and the axle of the pulley M' to be disturbed by such shifting of the wind.

The wind-wheel consists of the hub E, having sockets e for the blades e' and a flange or disk, e², to which the blades are bolted, and the blades are braced by the hoops e³, passing through the blades, and the hoops e⁴, secured to the edges of the blades. The blades, being solid, may be used without additional sails, or sails may be secured to the hoops between the blades, if desired.

What I claim is—

1. In a windmill, the rotary mast having a knee-joint thereon at one side of its longitudinal center, in combination with the endless chain and the chain-pulleys supported at the upper and lower ends of the mast, substantially as shown and described.

2. In a windmill, the rotary mast having a knee-joint therein, the pivot of which joint is located to one side of the longitudinal center of the mast, to cause the upper part of the mast to incline slightly from a perpendicular, substantially as shown and described.

3. In a windmill, the rotary mast having a knee-joint therein, and having its upper part, c', slightly inclined from a perpendicular, in combination with one or more weights attached to the lower end of said part c', substantially as shown and described.

4. In a windmill, the rotary mast having a knee-joint therein, and having its upper part, c', slightly inclined from a perpendicular, in combination with a series of weights, a cord on which said weights are strung, and to which the lowest weight is secured, and supports attached to the mast and adapted to support the loose weights when the mast is erect, substantially as shown and described.

5. In a windmill, the rotary mast having a knee-joint therein, and having a pin passed through its upper end to form an axle for the wind-wheel, in combination with the wheel-hub having the chain-pulley secured thereto, the endless chain, the guide-pulleys on opposite sides of the knee-joint, and the chain-pulley at the lower end of the mast, substantially as shown and described.

6. In a windmill, the combination of the rotary mast, the chain-pulley supported at the lower end of the mast and mounted on a crank-axle having a roller on the crank, the annular guide-plates for said roller, and the oscillatory arms supporting said plates, substantially as shown and described, whereby the rotary motion of the crank shall be converted into a reciprocatory motion for operating a pump-rod, as specified.

7. In a windmill, the combination of the rotary mast, a crank or equivalent device supported in the mast, and means for operating the same, and a pivoted annular guide for the crank, substantially as shown and described, whereby the crank may be carried around with the mast, and the said pivoted annular guides may be continuously oscillated or reciprocated at the same time.

8. The wheel consisting of the hub E, having flange e², the blades e', bolted to the flange, and the brace-hoops e³ e⁴, the hoops e³ passing through the blades, and the hoops e⁴ secured to the edges of the same, substantially as shown and described.

9. In a windmill, the combination, with a supporting-frame, a rotary mast, and means for imparting a reciprocating motion to a pump-rod from the mast, of a table arranged above the pump-rod-operating mechanism and detachably connected to said mast, and a chain-pulley journaled in the mast above the table, substantially as herein shown and described.

JOSHUA G. BENSTER.
